ATTORNEY

UNITED STATES PATENT OFFICE.

GEORGE W. BROOKS, OF TOPEKA, KANSAS.

NAILING INSERT.

Application filed March 27, 1925. Serial No. 18,822.

This invention relates to a nailing insert. It is particularly designed to be used in connection with brick work, masonry, concrete and the like.

8 The primary object of the invention is to provide a nailing insert which will guide nails, screws or the like in a straight line and prevent their turning or bending due to resistances set up in the masonry, brick work 10 or concrete.

In carrying out the invention I may utilize a corrugated sheet of lead or some similar ductile material, the surface of which may, or 15 may not, be coated with glue, sawdust or some other appropriate medium and in some cases the corrugated sheet may be provided with an enclosing casing in the form of a grid with two walls between which the sheet is received. The grid like walls of the casing 20 permits mortar or concrete to flow between the spaces formed by the grid so as to act as an efficient bond to hold the casing between the courses of brick or masonry, the casing, however, is not necessary in all instances.

The novelty of my invention will be specifically described hereinafter, reference being had to the following description in connection with the accompanying drawings, in 30 which

Fig. 1 is a fragmentary, perspective view of one corner of a room constructed of bricks for the walls and concrete for the floor, the casing with the corrugated sheet being shown 35 in the wall and the corrugated sheet alone being shown in the concrete floor.

Fig. 2 is a perspective view of the corrugated insert.

Fig. 3 is a perspective view of a modified 40 form of insert.

Fig. 4 is a perspective view of a further modified form of insert.

Fig. 5 is a sectional view through part of a 45 concrete floor with the form of insert, shown in Fig. 2, imbedded therein and showing a nail partly driven into the concrete, and

Fig. 6 is a perspective sectional view of the corrugated sheet and casing.

In Fig. 2 I have shown a simple form of 50 insert as comprising a corrugated sheet 1 of lead although other material may be used, however, I prefer to use lead because it is soft, pliable and easily formed into sheets and because it is especially adapted for the purpose of this invention. The corrugated portions

2 and 3 alternate so as to form guide grooves 4 and 5 on opposite sides of the sheet 1. The sheet is inserted endwise so that the nails, screws or the like may be driven longitudinal of the corrugations. The corrugated walls 60 serve as guides for the nails, screws or the like and wherever desired I may coat the surfaces of the sheet with a suitable friction material, such as glue, sawdust or the like. The coated sheet is best illustrated in Fig. 3. 65 Here the sheet is rolled in cross section, one end 6 being in the center and the other end 7 on the outside of the roll, the roll may be loosely made. As before stated, either before or after the sheet is rolled, it may be provided with a covering 8 of glue, sawdust or the like.

In Fig. 4 I have shown a plurality of sheets 9, 10 and 11 all generically corresponding to the sheet 1. The ends of the sheets being 75 connected by fold 12 and 13 so, in fact, the sheets 9, 10 and 11 (arranged substantially parallel) are parts of one continuous sheet.

In Fig. 5 the form of insert (shown in Fig. 2) is illustrated as imbedded in the concrete 80 base or mass 14. By concrete I mean any cementitious mass or body. In Fig. 5 I have also shown how the nail 15 may be driven into the concrete in a straight line, guided as it is in one of the grooves of the nailing 85 insert. It will be apparent that liability of the nail turning or bending will be eliminated because the entire longitudinal surface will be supported by the walls of the guiding grooves as the nail is driven in.

In Fig. 6 I have shown the strip or sheet I received in a holder or casing, the casing being illustrated as comprising a sheet of metal 16 bent intermediate its ends as at 17 to form two substantially parallel walls 18 and 19, the walls being slotted as at 20 and 21 so that the edges of the slots can be turned outwardly, the free ends of the holder or casing being brought together at 26, which is really the rear end of the casing. The casing 100 is preferably used in connection with the sheet as an anchor where the nailing insert is to be placed between courses of brick or masonry in the mortar joints.

In Fig. 1 I have shown how the casings or 105 holders are applied in the mortar joints 27 between the bricks 28.

It will be seen from the foregoing that I have provided a simple, inexpensive, easily constructed nailing insert which will prevent 110

the nails from bending as they are driven into the hard walls and while I have specifically described at this time what appears to me to be the very best forms of my invention I would have it understood that I do not wish to be limited to the exact details of construction shown, but reserve the right to make such changes as properly come within the scope of the appended claims.

10 What I claim and desire to secure by Letters-Patent is:—

1. A nail guide comprising a corrugated sheet, the corrugations providing angularly related walls constituting nail guides upon

15 opposite sides of the sheet for frictionally engaging the nail to prevent its separation from

the sheet, the corrugations being faced with friction material.

2. A nail guide comprising a sheet having staggered longitudinal channels, the walls of the channels providing adjacent guides for nails, and a holder therefor consisting of parallel bodies provided with slots disposed transversely to said channels of the sheet.

3. In combination with a nail guide, a holder comprising spaced slotted walls receiving the guide, the walls having outstriking portions transversely disposed to the axis of the guide, outstriking of said portions producing said slots.

In testimony whereof I affix my signature.

GEORGE W. BROOKS.
